UNITED STATES PATENT OFFICE.

THOMAS R. LEES AND ROBERT T. LEES, OF WESTPORT, CONNECTICUT,
AND JAMES E. LEES, OF NEW YORK, N. Y., ASSIGNORS TO THE LEES
MANUFACTURING COMPANY, OF WESTPORT, CONNECTICUT.

DESIGN FOR AN ORNAMENTAL CABLE-CORD.

SPECIFICATION forming part of Design No. 17,014, dated December 7, 1886.

Application filed October 18, 1886. Serial No. 216,592. Term of patent 7 years.

To all whom it may concern:

Be it known that we, THOMAS R. LEES and ROBERT T. LEES, of Westport, in the county of Fairfield and State of Connecticut, and 5 JAMES E. LEES, of the city and State of New York, have invented a new Design for Ornamental Cable-Cord, of which the following is a specification.

This ornamental cable-cord is shown of about 10 the ordinary size in Figure 1, and in magnified size in Fig. 2 to represent the design more clearly.

The cable-cord *a* is ornamented by narrow helical bands *b* on the surface thereof, crossing each other in opposite directions, and contrasting in shades of colors with the cord and with diamond-shaped spaces between, and 15 forming an ornamental design that adds greatly to the beauty of the cable-cord, especially

when such cable-cord is made up into fringes 20 and other ornamental articles.

We claim—

The design for the ornamental cable-cord herein shown and described, the same consisting of a cable-cord having the helical bands *b* 25 on the surface thereof crossing each other in opposite directions, and contrasting in shades of color with the cable-cord showing through the intervening diamond-shaped spaces, substantially as set forth.

Signed by us this 15th day of October, 1886.

THOMAS R. LEES.
ROBERT T. LEES.
JAMES E. LEES.
